UNITED STATES PATENT OFFICE

DANIEL LAWRENCE BRAINE, OF BROOKLYN, NEW YORK, ASSIGNOR TO THE RAIL JOINT COMPANY, OF NEW YORK, N. Y., A CORPORATION OF NEW YORK

BULLDOZED COMPROMISE JOINT BAR AND BLANK

Application filed June 5, 1929. Serial No. 368,607.

This invention relates to improvements in rolled or forged bars or blanks from which compromise joint bars, for connecting and holding the ends of rails of different section 5 with their surface and gage in alinement, are adapted to be formed by a squeezing or bulldozing operation; also to an improved compromise joint bar of the squeezed or bulldozed type produced from the present bar or 10 blank.

For simplicity and economy in production, and because of other resulting benefits thoroughly appreciated by those skilled in the rail joint art, it is extremely desirable to 15 manufacture a compromise joint bar by a method involving rolling, forging or otherwise suitably forming a bar or blank to fit the high rail of a compromise or step joint combination of rails and to bulldoze, i. e. 20 squeeze or press a portion of such bar or blank to fit the low rail of the combination, and to compensate for the difference in height of the rails.

Bulldozing a rolled or forged bar or blank 25 to produce a compromise joint bar involves pressing or squeezing a portion of the bar or blank to reduce its height, thus to provide the low fishing section of the bar; also it involves vertically and laterally offsetting this 30 low fishing section to compensate for the difference in height and width of the rails and differences in width of rail heads at gauge point. Due, however, to the practical impossibility of taking an ordinary bar of 35 uniform height throughout its length and effecting an abrupt vertical offset between different portions thereof by a bulldozing operation, compromise joint bars of the bulldozed type, as previously produced, have 40 been objectionable chiefly because they did not afford head fishing contact of the low rail section of the bar extending to the end of the low rail, nor base fishing contact of the high rail section of the bar extending to the end 45 of the high rail. To the contrary these con-

tacts, due to the curvature imparted to the bar at the junction of the high and low rail sections thereof by drawing of the metal of the bar as a result of the bulldozing operation, invariably terminated an objectionable 50 distance spaced from the ends of the rails, with consequent failure to provide support for the rails at the very point where good support is extremely to be desired.

The present invention therefore has in 55 view to provide a rolled or forged bar or blank with a distribution of metal such that when the bar is subjected to vertical offsetting by a bulldozing operation to provide a compromise joint bar, the head and base fishing 60 surfaces of the high and low sections of the resulting compromise bar will terminate at their inner or adjacent ends substantially in the same plane transversely of the bar, thereby to afford fishing contact and support of 65 the bar at the extreme ends of the rails where support is most desirable.

With the foregoing general purpose in view, the invention consists in the features of novelty as will be hereinafter more fully described, illustrated in the accompanying drawings and defined in the appended claims.

In the drawings wherein like characters of reference denote corresponding parts of the different views:

Figure 1 is a side elevation of a compromise rail joint effected by means of a compromise joint bar produced in accordance with the present invention.

Figure 2 is a perspective view of the blank or bar from which the compromise type of bar illustrated in Figure 1 is produced.

Figure 3 is an end view of the blank or bar shown in Figure 2; and

Figure 4 is a diagrammatic side elevation of a bulldozed compromise rail joint as heretofore produced, illustrating the lack of contact between the bar and the rails which is eliminated by means of the present invention.

In carrying out the present invention a bar or blank A of any desired cross section, capable of being bulldozed to produce a compromise joint bar, is rolled, forged or otherwise formed of a height to approximately fit the high rail of the particular step joint combination of rails with which the bar is intended ultimately to be used.

In accordance with common practice a portion of the bar A is adapted to be squeezed or pressed, i. e., bulldozed, to reduce the height thereof to produce the low fishing bar section 10 to fit the low rail of the particular step joint combination of rails with which the bar is intended for use, and in order to compensate for the difference in the height of the rail the bulldozing operation includes offsetting of the low fishing section 10 of the bar with respect to the high fishing section 12 thereof.

Heretofore, due to the bar or blank A being of uniform height throughout its length, offsetting of the low fishing section 10 with respect to the high fishing section 12 thereof has resulted in the intermediate portion of the head 14 and the base 16 of the bar, at the junction of the high and low fishing sections thereof, taking the form of a gentle curve extending a considerable distance longitudinally of the bar with the result, as shown in Figure 4 of the drawings, that the base fishing contact of the high fishing section 12 of the bar terminated an excessive distance from the end of the high rail and the head fishing contact of the bar with the low rail terminated an excessive distance from the end of the low rail. This lack of contact obviously may be reversed with relation to the high and low rails in cases where the depth of the head of the low rail is greater than the depth of the head of the high rail.

To compensate for the draw of the metal of the bar incident to vertically offsetting the low fishing section 10 thereof the present invention contemplates an addition of metal to the head 14 and the base 16 of the bar intermediate the ends thereof so that when the bulldozing operation is performed a substantially abrupt shoulder will be produced at the junction of the head and base portions of the high and low rail sections of the bar. These additions of metal designated 18 and 20, respectively, are built up upon the fishing surfaces of the head and base of the bar so that, primarily, it is these fishing surfaces that are affected, the metal of the additions or protuberances 18 and 20 being so distributed—of greater cross section intermediately and tapering towards the ends of the bar, gradually merging into the latter, for example—that the abruptness of the shoulder formed at the junction of the high and low fishing sections 10 and 12 is so pronounced that the head and base fishing surfaces of the high and low fishing sections 10 and 12 terminate

substantially in the same plane transversely of the bar. This means of course that when the bar is incorporated in a joint as illustrated in Figure 1 both the head and the base fishing contacts of the bar with the rail will extend entirely to the end of the rail thereby providing complete and efficient support for the latter.

A bar produced in accordance with the present invention may or may not be provided with a central reinforcement on the outer face of the web thereof, as desired. A central reinforcement such as is disclosed in Armstrong Patent 1,663,619 may, for example, be conveniently formed on the bar.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:

1. A blank from which a compromise joint bar is adapted to be bulldozed provided with a fishing surface having medial enlargement of metal within planes defining the inner and outer limits of said surface to compensate for draw of the metal of the blank incident to vertically offsetting the blank to compensate for the difference in the height of the rails.

2. A blank from which a comprise joint bar is adapted to be bulldozed comprising a head, a web and a base, and a body of metal protruding upwardly from the head of the blank at the proposed point of junction of the high and low fishing sections of the finished bar, distributed to compensate for draw of the metal incident to vertically offsetting the blank to compensate for the difference in the height of the rails.

3. A blank from which a compromise joint bar is adapted to be bulldozed comprising a head, a web, and a base, and a body of metal protruding downwardly from the base of the bar at the proposed point of junction of the high and low fishing sections of the finished bar, distributed to compensate for draw of the metal of the blank incident to vertically offsetting the blank to compensate for the difference in the height of the rails.

4. A blank from which a compromise joint bar is adapted to be bulldozed comprising a head, a web and a base, and separate bodies of metal protruding upwardly from the head and downwardly from the base of the bar, respectively, at the proposed point of junction of the high and low fishing sections of the finished bar, distributed to compensate for draw of the metal of the blank incident to vertically offsetting the blank to compensate for the difference in the height of the rails.

5. A blank from which a compromise joint

bar is adapted to be bulldozed inclusive of a fishing surface provided intermediate its ends and within its inner and outer limits with a body of metal of greatest thickness intermediate its ends and merging into said bar to compensate for the draw of the metal of the blank incident to offsetting the blank to compensate for the difference in the height of the rails.

10 In testimony whereof I hereunto affix my signature.
